UNITED STATES PATENT OFFICE.

FREDERICK FERRIS, OF BAYONNE, NEW JERSEY.

COMBINED SHADE-ROLLER BRACKET AND CURTAIN SUPPORT.

Application filed November 23, 1922. Serial No. 602,797.

To all whom it may concern:

Be it known that I, FREDERICK FERRIS, a citizen of the United States, and resident of Bayonne, in the county of Hudson and State 5 of New Jersey, have invented certain new and useful Improvements in Combined Shade-Roller Brackets and Curtain Supports, of which the following is a specification.

10 This invention relates to improvements in combined shade roller brackets and curtain supports.

The object of the invention is the production of a bracket and support, that can easily 15 be fastened to the frame of a window, for the purpose of supporting a shade roller and one or a plurality of curtains. A second object of the invention is the production of combined brackets and supports, whereby 20 shade rollers of various lengths and curtains of different widths can be easily supported in place without changing the locations of the brackets and supports, after being fastened in place. A third object of 25 the invention is the production of means, whereby a shade roller can be supported at different levels. A fourth object of the invention is the production of shade roller brackets with detachable curtain supports, 30 whereby curtains can be easily and detachably locked to their supports.

The invention is founded on the principle of adjustably supporting a shade and curtain in place.

35 In the accompanying drawings Fig. 1 represents a front elevation of an exemplification of a pair of combined shade roller brackets and curtain supports with fragmentary portions of curtains and a fragmentary portion of a shade roller; Fig. 2 shows a top plan view of Fig. 1; Fig. 3 indicates a left hand end view of Fig. 1 with a section of Fig. 1 on the line 3, 3; Fig. 4 indicates a top plan view of a detail; Fig. 5 40 is a left hand end view of Fig. 4; Fig. 6 represents a front elevation of a detail; Fig. 7 shows a top plan view of Fig. 6; Fig. 8 is a left hand end view of Fig. 6; Fig. 9 represents a front elevation of a modification of 45 the shade roller brackets and curtain supports with fragmentary portions of curtains and a fragmentary portion of a shade roller; Fig. 10 is a top plan view of Fig. 9; Fig. 11 shows a left hand side view of Fig. 9; Fig. 55 50 55 represents a top plan view of a detail; Fig. 12 is a top plan view of a detail; Fig. 13 is a section of Fig. 9 on the line 13,

13; and Fig. 14 shows a section of Fig. 9 on the broken line 14, 14. Referring to Figs. 1 to 8 inclusive each bracket and support comprises the supporting bar 20, that has extending from its upper face the longitudinal 60 guide strips 21. A vertical web 22 extends up from the upper surface of the bar 20 and joins with the horizontal flange 23. A vertical flange 24 extends from the horizontal 65 flange 23 and has formed therewith the clamping lugs 25. Openings are formed in the vertical flange 24 for the screws 26 to fasten it to the window frame 28. A pair 70 of brackets are indicated in their entirety by the letter A. Each of said brackets comprises a box shaped upper portion with the bottom wall 32, the front and rear walls 33, and the top walls 34 with depending flanges 35, forming hook ends a. An arm 36 with 75 a plurality of journal openings 37 extends from the bottom wall 32 and is inclined thereto. A shade roller 38 has its journal pins 39 supported in a pair of the openings 37 in said arms 36. The bracket A is slidably supported on the supporting bar 20, the hook ends a engaging the guide strips 21. Threaded openings are formed in the walls 33 for the clamping screws 40, which clamp 80 the bracket A to the supporting bar 20. The bracket A may be supported on the bar 20 as indicated in Fig. 3 of the drawing with the arm 36 inclined toward the window frame 28 or reversed thereto inclined away from the said window frame. By this means 85 the shade roller 38 may be either located adjacent to or spaced from the window frame 28. A pair of supporting frames are each indicated in their entirety by the letter B. Each frame B comprises the flange 95 42 which has formed therewith the supporting blocks 43. Pairs of clamping hooks 44 extend from the top faces of the blocks 43. A tapered shank 45 extends from the lower edge of the flange 42 and is shaped to engage the clamping lugs 25 to detachably secure the frame B in place. A curtain support is designated in its entirety by the letter C and comprises the longitudinal members 48 and 49. The member 48 has extending therefrom a shank 50 that telescopes with a box shaped end 51 of the member 49. Each of the members 48 and 49 are preferably rectangular in cross section and have respectively formed at their outer ends the 100 arms 55 and 56. A flange 57 with openings 58 extends from each of said arms. The 105 110

openings 58 detachably lock with the hooks 44 of the supporting frames B and a vertical end wall 59 of each of the arms 55 and 56, bears against the vertical face of one of the 5 supporting blocks 43.

A second curtain support is designated in its entirety by the letter D and comprises the longitudinal member 62, with the arms 63 that are similar to the arms 55 and 56. 10 The arms 63 have formed therewith flanges 64 with openings, similar to the flanges 57 and end walls 66 similar to 59 are formed with the arms 63. Each of the arms 63 is locked with a pair of the hooks 44, and 15 each end wall 66 bears against the front face of one of the supporting blocks 43. Curtains 67 and 68 are respectively supported on the curtain supports C and D.

Referring to Figs. 9 to 14 inclusive each 20 bracket and support comprises the supporting bar 70, that extends forwardly from the rear flange 71. A longitudinal upper groove 72 is formed between the bar 70, and the flange 71. The flange 71 has formed there- 25 with an extension 75 at one end of the bar 70, and at the upper portion of said extension are formed the tapered clamping lugs 76. Openings are formed in the flange 71 for the screws 77 to fasten it to the window frame 28. A bracket is indicated in 30 its entirety by the letter A¹, and comprises the box shaped upper portion with the top wall 82 having the depending heel 83, the front wall 84 and the bottom wall 85. An 35 arm 86 with a plurality of journal openings 87, extends from the walls 84 and 85. The shade roller 38 is supported in the arms 86 as already described. The bracket A¹ is 40 slidably supported on the supporting bar 70, the heel 83 extending into the groove 72. A clamping screw 92 is in threaded engagement with an opening in the top wall 82 of the bracket A¹ and its end bears on the bar 70. Supporting frames B as already 45 described are detachably connected to each bracket and support having the bar 70. Curtain supports C and D as already described are detachably connected to the supporting frames B as already described.

50 Referring to Figs. 1 and 2 to locate the shade roller 38 in place, the brackets A are moved on the supporting bars 20 to properly position them for the journal pins 39 of

the shade roller. To locate the curtains 67 and 68 in place they are drawn over the 55 curtain supports C and D and then the arms of the latter are locked with the hooks 44. The curtain support C on account of its telescopic feature permits curtains of different widths to be used. Instead of the 60 curtain support D, a second curtain support similar to C may be used.

Having described my invention what I desire to secure by Letters Patent and claim is:

65 1. In a shade roller bracket and curtain support the combination of a supporting bar having longitudinal guides extending from its upper surface, said bar having a vertical web, said web joining with a horizontal flange and the latter joining with a vertical flange, said vertical flange having a pair of clamping lugs formed therewith, a bracket having a box shaped portion with hook ends 70 slidably supported on said bar, said hook 75 ends engaging the longitudinal guides of the supporting bar, said box shaped portion having an arm extending therefrom, means to clamp the box shaped portion to the supporting bar, said arm having an opening 80 to support the journal pin of a shade roller, a supporting frame detachably locked with the clamping lugs of the supporting bar and one end of a curtain support detachably locked with said frame.

85 2. In a shade roller bracket and curtain support the combination of a supporting bar having longitudinal guides extending from its upper surface, a pair of clamping lugs for said bar, a bracket having a box shaped portion with hook ends slidably supported on said bar, said hook ends engaging the longitudinal guides of the supporting bar, said box shaped portion having an arm 90 extending therefrom, means to clamp the box shaped portion to the supporting bar, said arm having an opening to support the journal pin of a shade roller, a supporting frame detachably locked with the clamping lugs of the supporting bar and one end of a curtain support detachably locked with said frame.

95 Signed at Bayonne, in the county of Hudson and State of New Jersey, this 4th day of November, A. D. 1922.

100 FREDERICK FERRIS.
